UNITED STATES PATENT OFFICE

133,226

DESIGN FOR A CIGARETTE HOLDER

Robert C. Wilson, Louisville, Ky.

Application June 2, 1941, Serial No. 101,264

Term of patent 3½ years

To all whom it may concern:

Be it known that I, Robert C. Wilson, a citizen of the United States, residing at Louisville, in the county of Jefferson and State of Kentucky, have invented a new, original, and ornamental Design for a Cigarette Holder, of which the following is a specification, reference being had to the accompanying drawing, forming part thereof.

I claim:

The ornamental design for a cigarette holder, as shown.

ROBERT C. WILSON.
